DESIGN FOR A COAT

Abraham Levine, New York, N. Y.

Application April 12, 1939, Serial No. 84,230

Term of patent 3½ years

To all whom it may concern:

Be it known that I, Abraham Levine, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein

The characteristic feature of my design resides in the combination on the coat disclosed of the particular embroidery on the sleeves, as shown.

I claim:

The ornamental design for a coat, substantially as shown, and described.

ABRAHAM LEVINE.
